UNITED STATES PATENT OFFICE.

JOHN EDWARD OGDEN, OF CORNWALL, NEW YORK.

SHEET-METAL BOLT-ANCHOR.

1,305,000.

Specification of Letters Patent. Patented May 27, 1919.

Application filed December 24, 1914. Serial No. 878,844.

To all whom it may concern:

Be it known that I, JOHN EDWARD OGDEN, a citizen of the United States of America, and a resident of Mountainville, town of 5 Cornwall, county of Orange, and State of New York, have invented certain new and useful Improvements in Sheet-Metal Bolt-Anchors, of which the following is a specification, reference being had to the accompanying drawings, forming a part thereof.

My invention relates to bolt anchors and the like and has special reference to such as are formed from sheet metal.

One object of my invention is to provide 15 a simple device of the aforesaid character which may be manufactured in large quantities at small cost and which shall possess the combined advantages of cast metal anchors and sheet metal anchors as hitherto 20 constructed. In other words, it has been my aim to provide a sheet metal anchor which may be produced by a simple punching or stamping process and have the resiliency of sheet metal while it at the same time has 25 walls of varying thickness as well as a tapering opening and is adapted to receive the threads of a bolt.

While the bolt anchors of my invention may be readily formed from commercial 30 sheet metal such as sheet iron, steel, or copper, having a substantially uniform thickness, I have used the term "sheet metal" herein in a broader sense and intend to include not only what is commonly known 35 as sheet metal but also rolled metal such as lead, or cast or wrought metal such as malleable iron which is adapted to be folded to produce the results desired.

Other objects and advantages of my invention will be set forth hereinafter, and in order that my invention may be thoroughly understood, I will now proceed to describe the same in the following specification and then point out the novel features thereof in 45 appended claims.

Referring to the drawings:

Figure 1 is a side elevation of a bolt anchor formed in accordance with and embodying my invention.

50 A longitudinal section of the same anchor is shown in Fig. 2.

Fig. 3 is an end elevation of the anchor and

55 Fig. 4 is a sectional view taken on the line 4—4' of Fig. 2.

Fig. 5 shows a development of the anchor into one plane

Fig. 6 is a view corresponding to Fig. 5 and illustrates the application of my invention to a two-part anchor instead of to a one-piece structure.

Various modifications of my invention are shown in side elevation in Figs. 7, 9, 11 and 13, and in end elevation in Figs. 8, 10, 12 and 14, the end views being drawn to a larger scale.

Still another modification is shown in Fig. 15.

Fig. 16 is a side elevation of another modification of my invention.

Fig. 17 is an enlarged sectional view of the same, taken on the line 17—17 of Fig. 16 and

Fig. 18 is a development of the body of the anchor, into a single plane.

Another modification of my invention is shown in longitudinal section in Fig. 19 and side elevation in Fig. 20.

Fig. 21 is a sectional view of the same, taken on the line 21—21 of Fig. 20 and

Fig. 22 is an end elevation with a part of one wall broken away and shown in section.

A development of one of the sheet metal parts of the same structure is shown in Fig. 23.

Fig. 24 is a sectional view showing a portion of another form of anchor which also embodies my invention, and in which the thickness of metal is increased by a single overlap in one section and a double overlap in the adjacent section.

My invention is obviously not restricted to either a one or a two-piece anchor, and in fact it is equally applicable to an anchor composed of any number of parts.

The structures shown in the drawings are intended only to illustrate my invention and it is evident that various other modifications may be produced within the spirit and scope of my invention and I intend that only such limitations be imposed as are indicated in appended claims.

Referring to Figs. 1 to 5 of the drawings, the structure here shown comprises an anchor or shell 20 having a substantially cylindrical exterior—that is, adapted to largely engage the walls of a cylindrical hole—and a tapered opening 21 which is circular at its outer end and is elliptical in form at its inner end. The shell comprises two members

20^a and 20^b which may be integral and have the form shown in Fig. 5 when developed into a single plane, or separate parts each having the form shown in Fig. 6. In the 5 form shown in Fig. 5, the unit comprises a plate having transverse ribs or corrugations 22, a rectangular middle section 23 which forms a part of the outer end of the shell and is provided with notches 24 and a central hole 24^a, and fan-shaped end sections 25 which flare away from the rectangular section 23 and form the inner end of the completed shell.

As clearly shown in Fig. 1, the flaring corners 25^a and 25^b of the section 25 are folded back upon the central portion of this section and overlap each other. The lines upon which the wings 25^a and 25^b are folded are not continuations of the sides of the rectangular section 23 but are tapered as shown in dotted lines 26, in Fig. 5. By this means the opening 21 of the shell is made tapering, as clearly shown in Figs. 2, 3 and 4. The members 20^a and 20^b are bent into substantially cylindrical form and the outer end of the shell is fashioned by drawing the same through a suitable die. If the members are made in separate pieces they are united at their outer ends along the edges 27 by soldering, welding or some other suitable means.

Attention is directed to the fact that while the interior opening 21 is tapered for the reason above set forth, the outer surface of the shell is substantially cylindrical as already explained because the walls at the inner end are thickened by the folding of the portions 25^a and 25^b. The sections 22 together constitute means for receiving the threads of a bolt, the corrugations being 40 suitably inclined to the axis to effect this result.

While I have referred to the opening as a "tapered opening" it may be either uniformly tapered throughout or tapered only in a certain section or sections and otherwise cylindrical; in fact it is usual to having a cylindrical section near the middle or at the outer end of the opening.

The anchor is used in a well known manner, by being driven into a hole in a wall of concrete or like material which will not hold the threads of a bolt, and a bolt or other screw-threaded member which is to be supported, screwed into the anchor. As the 55 bolt is being inserted it expands the anchor on account of the tapered opening 21 and causes it to be very securely fastened in the wall in which it is placed.

The folded wings 25^a and 25^b have another important function, *i. e.*, that of materially assisting in preventing the removal of the shell after it has been expanded.

The corners of the wings may be cut off and bent outwardly, forming relatively short longitudinal ribs 30, as shown in Figs.

7 and 8. This modification of my invention is otherwise similar to the structure above described.

As shown in Figs. 9 and 10, the rectangular portion 23 of the anchor may be indented to form grooves 31 or the metal may be forced outwardly to form outwardly extending ribs 32 as shown in Figs. 11 and 12. The ribs are not necessarily longitudinal but may extend at an angle as shown at 33 in 75 Figs. 13 and 14. These ribs tend to prevent rotation of the sleeve in the hole into which it is inserted. The grooves 31 provide pockets into which wedges or nails may be driven between the shell and the wall, and so prevent the rotation of the shell.

In order to assist in preventing the removal of the shell from the hole, lateral ribs such as the ribs 34, shown in Fig. 15, may be employed.

The inner ends of the shells may be provided with ribs or projections either in place of those at the outer ends or in addition to them. For example, the overlapping wings 25^a and 25^b may have projections as shown at 60 in Fig. 9. Ribs, such as 61 (see Fig. 11), may be formed in the corrugated part of the shell under the wings and serve to increase the resiliency of the shell by holding out the wings. The ribs may be formed by 95 pressing out the metal either with or without cutting the sheet metal. Various combinations of different forms of ribs or projections may be effected within the scope of my invention.

Referring to Figs. 16 and 17 the anchor here shown comprises a cylindrical body 36, the walls of which are increased in thickness near its outer end as shown at 37. The inner end of the body is flared at 38 and 105 slots 39 are provided in opposite sides of the body which open into diamond-shaped holes 40 in the flaring section 38. In addition to the cylindrical body the anchor comprises a nut 41 having conically curved exterior 110 walls to form a plug and diamond-shaped projections 42 which extend into the holes 40. The arrangement of parts is such that after the anchor is inserted in a hole and a bolt or screw-threaded member screwed 115 into the nut 41, the nut will be drawn into the flared end of the anchor which will be expanded, both on account of the conical shape of the nut and on account of the wedge shape of the projections 42 which advance into the slots 39.

The body of this anchor is formed from sheet metal and when developed into a single plane has the shape shown in Fig. 18. The metal stamping from which the anchor 125 is formed has a rectangular portion 36^a in which the slots 39 and the holes 40 are cut and a projection 36^b which is narrower than the rectangular portion 36^a, and is provided with slots 39^a. The anchor is formed by 130

rolling the sheet metal stamping into a cylindrical form, the arrangement being such that the slots 39^a coincide with the slots 39 and form a part of them in the completed anchor. The projection 36^b wraps around the outside of the anchor and increases the thickness at its outer end. The inner end of the anchor is flared as already described.

The method outlined above may be employed with equal facility to a double expansion anchor having the arrangement of expansion members shown in Fig. 19. The stamping then would have two integral sections each like Fig. 18.

15 The thickening of the walls of a sheet metal bolt anchor, by folding, is also exemplified by the structure shown in Figs. 19 to 23 of the drawings. This modification may comprise either a two-part or a one-piece tubular body 45 which has a substantially cylindrical central section 46 and a pair of similar outwardly flaring end sections 47. The thickness of the central section is increased by folding so that the general form of the exterior of the anchor is cylindrical while its interior opening is tapered inwardly from each end.

In a two-part shell the sheet metal parts are identical and each of them has the form shown in Fig. 23, when developed into a single plane. The stamping as here shown has lateral projections 48 which are adapted to be folded back onto the body of the stamping on the dotted lines. The corners 35 of the stamping are provided with notches 49, the notch of one sheet metal part of the anchor coöperating with an adjacent notch of the other part, as clearly shown in Fig. 20, to provide a triangular opening 50.

40 A taper nut 51 having wedge-shaped lateral projections 52 is located in one end of the sheet metal shell, with the projections 52 disposed in the triangular openings 50 of the shell.

45 The taper collar 53 is provided with similar projections 54 which extend into the openings 50 at the opposite end of the shell. The two parts of the shell may be fastened together by any suitable means such as, for 50 example, resilient hoops 55.

The anchor is utilized in a well known manner, as clearly shown in Fig. 19. The nut 51 and the collar 53 having been mounted in the respective ends of the shell, 55 the latter is inserted in a hole as shown in the drawing with the nut 51 at the inner end of the anchor. A spacing collar 56 is interposed between the plate 57 which is to be secured by a bolt 58, and the taper collar 53. The arrangement of parts is such that when the bolt is turned the anchor is expanded, the nut 51 and the collar 53 being drawn toward each other.

Attention is directed to the fact that the 65 body of the anchor is reversible, and for

end, and the sheet metal stamping of which each of its parts is formed, is regular and symmetrical in shape.

The stamping for the one-piece shell will have two sections each resembling Fig. 23, 70 except that the wings will only be provided on the non-adjacent edges of the sections and may be made longer to provide the desired increase in thickness.

The folded wing arrangement may of 75 course be made single instead of double ended, if desired, only a single expansion member like the member 41 of Fig. 16 being employed.

In Fig. 24 I have shown a portion of a 80 shell one end of which is thickened by folding the metal three times instead of once. By this means the end of the shell has four thicknesses of metal as shown at 65 while the adjacent section has two thicknesses and 85 the opposite end only a single thickness.

The number of folds is not important and depends on the thickness of metal desired, for example the fold might be made double or quadruple instead of triple and 90 in the form of a tuck, plait or hem.

What I claim is:

1. A bolt anchor comprising a tubular body divided longitudinally, each part being formed by stamping or punching from 95 sheet metal and having transverse corrugations pressed in the metal to receive the threads of a bolt and having its inner portions over-lapped near one end to increase the thickness of the walls of the anchor. 100

2. A bolt anchor comprising a tubular body having a plurality of similar members of sheet metal, the inner portions of each of which has its walls thickened by folding the sheet metal together on itself, and each 105 having projections to constitute ribs near the end of the anchor.

3. A bolt anchor comprising a tubular body having two similar semi-cylindrical members of sheet metal, the inner portions 110 of each of which has its walls thickened by folding the sheet metal together on itself, and each having longitudinal projections to constitute ribs near the end of the anchor.

4. A bolt anchor comprising a tubular metal member having a tapered bore and having the thickness of its walls increased by folding the metal together near the smaller part of the tapered bore. 115

5. A bolt anchor comprising a tubular 120 metallic body having a plurality of members each having triangular portions overlapping the walls of said members and partially overlapping each other.

6. A bolt anchor comprising an integral 125 body having a plurality of members extending from an intermediate cylindrical portion, formed from stamping from sheet metal and having corrugations pressed in the metal to receive the threads of a bolt, 130

each of said members having portions folded together transversely over its walls and overlapping each other.

7. A bolt anchor comprising a tubular metal member having a tapered bore, the walls of said member having transverse corrugations to receive the threads of a bolt and having the thickness of its walls increased by folding the metal together near the smaller part of the tapered member.

8. A bolt anchor comprising a tubular metal member having a tapered bore, projections forming ribs near the end of the anchor and having the thickness of its walls increased by folding the metal together near the smaller part of the tapered member.

9. A bolt anchor comprising a tubular member having a tapered bore, the walls of said member having transverse corrugations to receive the threads of a bolt, projections forming ribs near the end of the anchor, said member having the thickness of its walls increased by folding the metal together near the smaller part of the tapered member. 26 25

In testimony whereof I have hereunto set my hand this 21st day of Dec., 1914, in the presence of two subscribing witnesses.

JOHN EDWARD OGDEN.
